WIRES ROPE

Heinrich Oechslin, Romanshorn, Switzerland

Application August 4, 1936, Serial No. 94,226
In Germany November 27, 1935

8 Claims. (CL 117—58)

Locked wire ropes are known, in which one or more layers of profile wires of sector-shaped or wedge-shaped cross section surround the core, and other profile wires engaging over one another 5 form an external closure or lock. This rope structure, on account of its limited flexibility and of the complicated constitution of its profile, is only suitable for cables of large cross section, for instance for carrying ropes of aerial cable ways.

10 Ropes are also known in which profile wires forming an outer layer interengage with one another in such a manner that projecting portions of a profile wire are embraced by recesses in adjacent profile wires, these profile wires mutually locking one another, and thereby preventing any broken wire from jumping out of the periphery of the rope. It has also been proposed, for 15 electrical conducting cables, to lodge filling wires, as projecting members, in longitudinal grooves in the profile wires, which touch one another with their lateral surfaces. The disadvantage of such rope and strand structures consists in the fact that in the event of breakage of a wire, the ends of the wire, in consequence of the rigid locking, 20 cannot protrude from their regular positions at all, and consequently the breakage of the wire remains undiscoverable.

According to the present invention, however, in wire rope strands or stranded ropes, profile wires of sector-shaped or other wedge-shaped cross section are provided, on their contacting lateral boundary surfaces, with recesses which are so dimensioned that they leave a clearance space in the locking direction for the filling wire embraced by them or for a projection substituted for the filling wire on one of the two profile wires.

The result is hereby obtained that any broken wire in the outer layer, though it cannot spring out of the peripheral surface of the rope, can protrude to a certain extent, thereby enabling the breakage to be perceived. With an outer layer and one or more inner layers of profile wires, in the event of a bending stress, an equalization of stress between the inner and outer wires is rendered possible, this being owing to the fact that the profile wires slide relatively to one another with their rubbing surfaces, and, as the rope or strand stretches, can slide back into their normal position again.

50 The invention is also correspondingly applicable to hollow ropes, strands or cables consisting of one or more layers of profile wires. In a multi-layer strand in which the outermost and innermost layers, or even all the layers, consist of profile wires with filling wires or corresponding

projections, by leaving out the core wire a cavity is formed, which, if the rope bends, enables the stresses to be equalized by displacement of the individual wires by means of the sliding surfaces. In particular the profile wires of the innermost 5 layer are in this case displaceable in the same manner as those of the outer layer.

The profile of the outer wires is preferably so selected that a circle touching all sides of the profile can be inscribed in it. In ropes according to this invention the flexibility is not materially impaired, as compared with those consisting of round wires, since the axes of the profile wires do not exceed, in the height and breadth of the sector profile, the diameter of a round wire. 10 In the case of the cross section of the strand being solid throughout the entire periphery, however, the wear is considerably reduced. Moreover wear is permissible in a more advantageous relationship to the cross section of the wire than in 15 the case of round wires.

With advancing mechanical wear, owing to baring or partial baring of the filling wires or of the recesses designed for their accommodation, the extent of the wear becomes perceptible. Accordingly, owing to the fact that the recesses are arranged at an appropriate distance from the periphery, the controlling dimension of the wear may be determined in advance.

Further features of the invention will be 30 gathered from the examples illustrated in the accompanying drawings, in which

Figure 1 shows the cross section of a strand in which profile wires are movably locked by filling wires;

Figure 2 is a perspective view on a larger scale of the lock shown in Figure 1;

Figure 3 shows in cross section one half of a wire rope made from strands such as the one shown in Figure 1;

Figures 4 to 10 show other forms of construction, each figure representing a quarter of the cross section of the strand;

Figures 4 and 5 illustrating a movable lock with projections embraced by recesses in the profile 45 wires;

Figure 6 showing a lock with filling wires of triangular cross section, and

Figure 7 a lock with projections and recesses of rectangular cross section in the profile wires;

Figure 8 showing one example of the employment of a profile wire of different cross section, and

Figures 9 and 10 showing further examples of the employment of wedge-shaped profile wires,

the lateral surfaces of which do not lie in planes passing through the axis of the cross section of the strand.

Figure 11 shows in cross section a hollow rope 5 or cable consisting of one layer of profile wires, the left hand half showing the section in its ordinary or straight condition and the right hand half showing the section when subjected to a bending stress, and

10 Figure 12 shows in cross section one half of a rope consisting of a plurality of layers of profile wires, for instance an overhead electric power current cable, with outer and inner movable locking.

15 In the strand illustrated in Figure 1, the core wires 1, 2 are surrounded by wires 3, which preferably have a profile which is circumscribed by a circle. The profile wires 3 are provided on their lateral surfaces 4 with recesses 5, which 20 brace filling wires 6 on both sides. The filling wires are preferably so stranded with the profile wires that they lie at the outer extremities of the recesses 5. The profile wire 7 shown in dotted lines, which is to be regarded as broken, and 25 which tends to spring out of the strand, is checked in its outward movement by the adjacent filling wires 6 on both sides. It can therefore only protrude a certain distance out of the strand, and a dissolution of the rope by the wires 30 springing out is prevented.

This type of movable locking will be more clearly understood from Figure 2. The profile wire 7 in the middle of this figure has not yet quite reached its extreme outer position, so that it does 35 not yet bear against the filling wires 6, which are held by the profile wires 3.

The rope illustrated in Figure 3 is produced by a known process, by stranding six strands 8, pertaining to a solid cross section and formed 40 as shown in Figure 1, with a hemp core 9.

45 In the case of the strands illustrated in Figure 4, the profile wires 10 have projections 11 on both sides, which engage in recesses 12 in the adjacent profile wires 13, so that a clearance space preferably remains both in an outward and an inward direction. By this means it becomes possible for both the wires 10 and the wires 13 to protrude from the strand to the extent of the outer and inner clearance respectively. It is in this case 50 immaterial whether the profile wires 10 and 13 are stranded with a core wire 14, or with a plurality of layers of core wires or profile wires.

The strand illustrated in Figure 5 is distinguished from that of Figure 4 merely by the 55 fact that the profile wires 15 are each provided with a projection 16 on one side and with a recess 17 on the other side.

The filling wires 18 of Figure 6, as distinguished from the filling wires 6 of Figures 1 and 3, are of 60 triangular cross section, and the recesses 19 in the profile wires 20 are shaped to correspond. The shapes of the cross sections of the filling wires and of the recesses are entirely optional. For instance filling wires of elliptical, hexagonal 65 or rectangular cross section may be employed.

In a similar manner it is possible to construct the projections and recesses of interengaging profile wires angularly. Thus the projections 21 and the recesses 22 of the profile wires 23 in 70 Figure 7 are rectangular in shape.

The profile wires 24 in Figure 8 are locked by filling wires 25 as in Figure 1. The locking is not affected by the difference in the profile of the wires 24.

75 Similarly in the case of the profile wires 26 and

27 of Figures 9 and 10, which abut upon one another with lateral surfaces extending at an angle to the axial plane of section, and with curved lateral surfaces respectively, the locking, as such, is not affected by the modifications in the 5 shape of the profile wires.

In the case of the hollow cable illustrated in Figure 11, the left hand half of the cross section shows the locking of the profile wires 30 with the filling wires 31 corresponding to those of 10 Figure 1. The right hand half of the cross section, however, illustrates how the profile wires 33 and the filling wires 34 become displaced under a bending stress, for instance in the event of a curvature of the rope over a bearing surface 32, 15 and render possible a change in relative position of the hollow rope cross section as a whole, thus equalizing the stresses.

In the case of the rope or cable of Figure 12, 20 consisting of a plurality of layers of profile wires, 20 the outer profile wires 35 are locked to the filling wires 36, and the inner profile wires 37 to the filling wires 38, in the manner shown in Figure 1, the inner movable locking also assisting in enabling the stresses to be equalized. The intermediate layer of profile wires 39 is shown by way of example without locking means. In the event of the core wire being absent, the central cavity 40 is formed. When employing this as an overhead power current cable, the filling wires consist for example of steel and the profile wires of 30 copper, aluminium or the like, the former constituting the supporting cross section and the latter the current-conducting cross section, or conversely. Alternatively the innermost layer of 35 wire (profile wires and filling wires of steel) takes the tensile stresses, while all the other wires (of copper, aluminium or the like) conduct the current or the like. In some instances it is sufficient if only a portion of the recesses designed for the 40 accommodation of the projections or filling wires are provided with filling wires or locked by means of projections, while the other recesses form empty cavities. A locking of the profile wires is also obtained for example if a filling wire is placed 45 in every other pair of abutting surfaces, since that would already be sufficient to prevent any broken wire from jumping out, since it would be locked on one side. Owing to the cavities, as is known in itself in cables with the core omitted, 50 oscillations, and also, in consequence of the greater bearing surface of the fastening position, corona losses, are diminished.

In Figures 1 to 7 and 11 are shown strands with twelve profile wires in the full cross section, and 55 in Figures 8 and 12 a strand or cable with eighteen outer profile wires. These numbers of profile wires are of course optional and are merely indicated by way of example.

For the essence of the invention it is moreover 60 immaterial whether they are employed in hollow ropes or in solid ropes, in hollow strands or in solid strands, in strands with a core wire or with internal layers of round wires or profile wires. It is furthermore unimportant whether the profile 65 wires, filling wires, projections and recesses are angular or rounded in cross section. The representation of the cross sections of profile wires and filling wires in the drawings is not intended to establish a definite standard. In particular the 70 dimensions of the filling wires and of the projections and recesses may be so selected, to adapt them to the cross-sectional form of the profile wires, which will depend upon the number thereof, that the springing out of a broken profile wire 75

is reliably prevented even if it is somewhat tilted. Profile wires and filling wires may consist of any suitable metals according to the purpose for which they are employed. The filling wires of 5 larger diameter may even be replaced by corresponding strands.

What I claim is:—

1. A wire rope or strand comprising an external layer of profile wires, the adjacent faces 10 of which are in sliding contact with one another, some at least of the profile wires being formed with recesses in their contacting faces, and locking elements engaging in the said recesses to prevent one profile wire becoming disengaged from 15 the others, the adjacent recesses forming apertures of elongated shape in cross section, the longitudinal axis of this cross section extending in the locking direction, and such clearance being provided between the locking elements and the 20 recesses as to allow limited relative displacement in the locking direction between adjacent profile wires.

2. A wire rope or strand comprising an external layer of profile wires the adjacent faces 25 of which are in sliding contact with one another, some at least of the profile wires being formed with recesses in their contacting faces, and filling wires engaging in the recesses in two adjacent profile wire surfaces and thus serving as locking 30 elements to prevent one profile wire becoming disengaged from the others, the adjacent recesses together forming an aperture of elongated shape in cross section, the longitudinal axis of this cross section extending in the locking direction, and 35 such clearance being provided between the filling wires and the recesses as to allow limited relative displacement in the locking direction between adjacent profile wires.

3. A wire rope or strand comprising an external layer of profile wires, the adjacent faces 40 of which are in sliding contact with one another, some at least of the contacting faces of the profile wires being formed with recesses, and projections on some at least of the contacting faces 45 of the profile wires, the said projections engaging in the recesses in adjacent faces and thus serving as locking elements to prevent one profile wire becoming disengaged from the others, the dimensions of the recesses being greater than those 50 of the projections in the locking direction, so as to allow limited relative displacement in that direction between adjacent profile wires.

4. A wire rope or strand comprising an external layer of profile wires the adjacent faces 55 of which are in sliding contact with one another, the profile wires being formed with recesses in their contacting faces, and locking elements engaging in some of the said recesses to prevent one profile wire becoming disengaged from the others, 60 the adjacent recesses forming apertures of elongated shape in cross section, the longitudinal axis of this cross section extending in the locking direction, the other recesses remaining empty, and such clearance being provided between the locking 65 elements and the recesses as to allow limited

relative displacement in the locking direction between adjacent profile wires.

5. A wire rope or strand comprising at least one layer of profile wires the adjacent faces of which are in sliding contact with one another, some at least of the profile wires being formed with recesses in their contacting faces, and locking elements engaging in the said recesses to prevent one profile wire becoming disengaged from the others, the adjacent recesses forming apertures 10 of elongated shape in cross section, the longitudinal axis of this cross section extending in the locking direction, and such clearance being provided between the locking elements and the recesses as to allow limited relative displacement 15 in the locking direction between the adjacent profile wires.

6. A wire rope or strand comprising an external layer of profile wires the adjacent faces of which are substantially plane radial faces in 20 sliding contact with one another, some at least of the profile wires being formed with recesses in their contacting faces, and locking elements engaging in the said recesses to prevent one profile wire becoming disengaged from the others, the 25 adjacent recesses forming apertures of elongated shape in cross section, the longitudinal axis of this cross section extending in the locking direction and in the direction of the radial contacting faces of the profile wires, such clearance being 30 provided between the locking elements and the recesses as to allow limited relative displacement in the locking direction between adjacent profile wires.

7. A wire rope or strand comprising an external layer of profile wires the adjacent faces of which are substantially plane non-radial faces in 35 sliding contact with one another, some at least of the profile wires being formed with recesses in their contacting faces, and locking elements 40 engaging in the said recesses to prevent one profile wire becoming disengaged from the others, the adjacent recesses forming apertures of elongated shape in cross section, the longitudinal axis of 45 this cross section extending in the locking direction and in the direction of the plane non-radial contacting faces of the profile wires, such clearance being provided between the locking elements and the recesses as to allow limited relative displacement in the locking direction between adjacent 50 profile wires.

8. A wire rope or strand comprising an external layer of profile wires the adjacent faces of which are curved surfaces in sliding contact with 55 one another, some at least of the profile wires being formed with recesses in their contacting faces, and locking elements engaging in the said recesses to prevent one profile wire becoming disengaged from the others, such clearance being 60 provided between the locking elements and the recesses as to allow limited relative displacement in the locking direction between adjacent profile wires.

HEINRICH OECHSLIN. 65
